UNITED STATES PATENT OFFICE.

JUSTIN R. WELLS, OF BROOKLYN, NEW YORK.

COMPOUND BALANCED STEAM-ENGINE.

SPECIFICATION forming part of Letters Patent No. 278,841, dated June 5, 1883.

Application filed December 15, 1882. (No model.)

To all whom it may concern:

Be it known that I, JUSTIN R. WELLS, of Brooklyn, Kings county, in the State of New York, have invented certain new and useful 5 Improvements in Compound Balanced Steam-Engines, of which the following is a specification.

I make an engine which is compact and may be conveniently portable, if desired, and which 10 is compound, by which I mean working the steam first in a small cylinder and expanding afterward in a larger one, the steam-pressure, momentum, and weight of its pistons and connections are perfectly balanced.

15 My invention consists in so arranging the cylinders and transmitting the power to the crank-shaft of a compound engine that all of the strains, either from steam-pressure or momentum of moving parts, are balanced, and by 20 this means all the friction the crank-shaft encounters in revolving in its bearings is that due to the force of gravity. The bed-plate, columns, &c., are also largely relieved from strain, and the vibration or throb caused by 25 the falling mass of one piston, piston-rod, and connecting-rod is entirely obviated by reason of the balance maintained by the simultaneously and equally ascending mass of the other piston and connected parts. By reason of this 30 relief from strain my engine can be constructed much lighter for the same power than any other form of engine, and on account of balanced momentum of moving parts I can attain a much higher piston speed, thereby reducing 35 the engine in size, weight, and cost below any at present constructed. I accomplish this in the following manner: The high and low pressure cylinders are placed in line, one on the top of the other, and rigidly connected. A rigid 40 partition separates the high-pressure cylinder from the low-pressure cylinder. The high-pressure piston connects by a piston-rod and connecting-rod to a central crank. The low-pressure piston connects by two piston-rods 45 and connecting-rods to two cranks, which latter are set directly opposite to the crank for the high-pressure piston, one on each side thereof. As the pistons work always in opposite directions, the valves of the two cylinders 50 can be correspondingly worked in opposite directions. I connect both to a single lever, so

that the weight of the valves is perfectly balanced. I employ a link-motion so arranged that a single link and actuating-eccentrics operate both valves. The shifting of the single 55 link changes the action of the steam in both cylinders equally under all conditions. The movement of the link to reverse reverses the action of both cylinders.

The following is a description of what I consider the best means of carrying out the invention.

The accompanying drawings form a part of this specification.

Figure 1 is an elevation viewed in the line 65 of the shaft, which shows the novel parts, with so much of the ordinary parts as is required to indicate their relation thereto. Fig. 1^a is a perspective detail, showing the relative positions of the cranks. Fig. 2 is an inverted plan, showing the two cylinders and the adjacent parts. Fig. 3 is a vertical section on the line s s, Fig. 2. Fig. 4 is a vertical section on the broken line t t, Fig. 2, showing the two cylinders with their respective pistons, piston-rods, and connecting-rods. 70 75

Similar letters of reference indicate corresponding parts in all the figures.

A is the smaller and high-pressure cylinder, and A' is the steam-chest therefor. B is the 80 larger or low-pressure cylinder, and B' is the steam-chest therefor. The small piston traversing in the high-pressure cylinder is marked a. A single piston-rod, a', fixed in the center thereof, connects to a cross-head, a'', which, 85 by means of a connecting-rod, a'', actuates one of the main cranks, a⁴, formed in or rigidly fixed to the main shaft O. The larger piston b in the low-pressure cylinder has two piston-rods, b' b'', fixed as near the rim as will allow 90 for suitable packings. These two piston-rods b' connect by two cross-heads, b'' b''', and two connecting-rods, b'' b''', with two main cranks, b⁴ b⁴, formed in or keyed to the main shaft O. The two cranks b⁴ are parallel to each other, 95 and are arranged on the shaft O, on the opposite side from the single crank a⁴.

C is the frame. C' C' are the outer slides. C² 100 are the inner slides. These slides guide the cross-heads. The slides C² serve both for the central cross-head, a'', and for the two outer cross-heads, b'' b'''.

D is a lever turning on a fixed axis, d , and receiving a vibrating motion through a pin, D', by means to be presently described. One end of the lever D actuates a valve, a^s , which 5 controls the action of the steam in the high-pressure cylinder A through a valve-stem, a^s , having a slot, a^s , which receives a pin, a^s , fixed on the lever D. The other end of the lever D actuates the valve b^s , which controls 10 the action of the steam in the low-pressure cylinder B. It is actuated by a stem, b^s , having a slot, b^s , which receives a pin, b^s , fixed in the lever D, and vibrating therewith.

The steam discharged from the exhaust-port 15 in the steam-chest A' of the high-pressure cylinder flows through a pipe, E, and serves as the live steam for the low-pressure cylinder B. The spent steam from the low-pressure cylinder is discharged through a pipe, F, into the 20 atmosphere, or into a condenser. (Not represented.) The shaft O carries two eccentrics, O' O², which receive straps O³, actuating eccentric-rods O⁴, connecting to a link, P. This is the open Stevenson link, well known in 25 steam-engineering, actuating the lever D by means of a link-block, D², which fits tightly and easily in the curved slot in the link, and embraces the pin D', so as to communicate the motion of that portion of the link P to the pin 30 D', and consequently to the lever D. The link P receives a liberal rocking motion and a slight bodily motion from the two eccentrics O' O², which are set nearly opposite to each other, and is controlled in position laterally 35 by a link, R', which connects to a hand-lever, R, turning on a fixed center, and adjustable by any ordinary or suitable means, so that it may cause the link P to work in all the positions required in practice for going ahead with 40 full steam, going backward with full steam, or going in either direction with various degrees of expansion of the live steam and of compression of the exhaust.

The pistons and their connections should be 45 of equal weight—that is to say, the small piston a and its single piston-rod a' , with its cross-head and connections, should be made heavy, and the large piston b , its two piston-rods, b' , its two cross-heads, b' , two connecting-rods, 50 b^s , and two cranks, b^s , should be made as light as consistent with strength, so that the parts will exactly balance each other, and the pistons will stand indifferently in any position in which they may be placed. When the engine 55 is running rapidly and the momentum of the parts becomes an important element, instead of, as in most engines, tending to violently shake the machine and its foundation, my engine will run with any required degree of speed 60 without any tendency to shake at all. My engine will run successfully in any position without being fastened to its foundation.

The valves a^s b^s should be of equal weight, and the actuating-pins a^s and b^s should be equi- 65 distant from the center d of the lever D. The valves thus perfectly balance each other; or,

if the valves be of different size and weight, the spaces between the ports should be correspondingly modified, and the distance of the actuating-pins from the center d of the lever 70 D may be arranged so that the moment of their inertia will be equal and the balance thus preserved.

The valves are actuated in equal times and to equal extents, always in opposite directions 75 the one to the other. The motion is derived through the link P, and the shifting thereof produces the usual effect of giving more or less movement to the valves. When there is a large movement the steam follows for both 80 in the large and small cylinder, and does not cushion in either. When the link is shifted to give less motion to the valves, the steam is cut off shorter and the exhaust is cushioned. My arrangement insures that the changes shall 85 be equal in both cylinders under all circumstances. Throwing the hand-lever R, and consequently the link P, from one extreme position to the other instantly reverses the action in both cylinders. 90

Modifications may be made in the forms and proportions. I can use flat ordinary slides with corresponding flat cylinder-faces, instead of the piston-valves and small cylinders for them to work in, which are shown. I can employ other means for connecting the lever D to the valve-stems. I can locate the pin D' nearer the end of the lever D. I can work the link P at a point intermediate between the lever D and the eccentrics, and employ a link 100 from the lever D to the link-block. In such case I shall make the curvature of the link the reverse of that shown and shift the block instead of the link, such arrangement being what is known in locomotives as "shifting-block," 105 as distinguished from the "shifting-link," motion.

One modification to which I attach much importance is to put the large cylinder below the small one, thus working the engine in the 110 reversed position to that shown. An objection to such arrangement is that the single piston-rod of the small piston would in such case have to pass through two stuffing-boxes or equivalent steam-tight devices, one in the fixed partition between the small cylinder and the large one, and another in the center of the large piston, either of which would be difficult of access for adjustment or repacking. I prefer the precise arrangement shown, for the reason, 115 among others, that only three stuffing-boxes are required for the three piston-rods, so that any leaks would instantly be discovered, and that each is easy of access for examination, adjustment, or repacking. 120

I propose in ordinary cases to employ a sleeve or casing which shall cover that portion of each of the two piston-rods b' b' where it runs close along the exterior of the small cylinder A.

The small cylinder may be made to embrace 130 and protect the adjacent portions of the two piston-rods b' b' for a long distance instead of

the short distance shown; or, all such embracing and protection may be omitted, it being of course understood that those piston- rods are necessarily stiff enough to maintain themselves, and that they are guided mainly or entirely by the cross-heads b^1 b^2 , running in the substantial slides C^1 C^2 C^3 .

Parts of the invention may be used without the whole. I can realize some of the advantages of the invention by other means of actuating the valves.

I claim as my invention—

1. The small cylinder A and larger cylinder B, arranged in line, as shown, in combination with the two pistons a^1 b^1 , moving in opposite directions, and with three piston-rods, cross-heads, connecting-rods, and cranks, arranged for joint operation as and for the purposes herein specified.
2. The valves a^5 b^5 and lever D, in combination with each other and suitable actuating

means, and with the small cylinder A and large cylinder B and their respective pistons and connections, arranged in line and adapted to serve as herein specified.

3. The compound engine described, having the small cylinder A and larger cylinder B, arranged in line as shown, in combination with the eccentrics O^1 O^2 , eccentric-rods O^4 , link P, adjusting means R R' , and lever D, operating the two valves a^5 b^5 , so as to regulate and reverse the action in both cylinders by the movement of a single member, R, as and for the purposes herein specified.

In testimony whereof I have hereunto set my hand, at New York city, New York, this 4th day of December, 1882, in the presence of two subscribing witnesses.

JUSTIN R. WELLS.
